FLUID MIXER

Lloyd W. Young, Elizabeth, N. J., assignor, by
mesne assignments, to Union Carbide and
Carbon Corporation, a corporation of New
York

Application June 9, 1934, Serial No. 729,777

3 Claims. (Cl. 158—27.4)

This invention relates to a fluid mixer and more particularly to an improved gas mixer for blowpipes which is especially adapted for first mixing air with a fuel gas, such as acetylene, and then mixing such acetylene-air mixture with substantially pure oxygen to provide an acetylene-air-oxygen combustible mixture capable of producing a welding or preheating flame.

In some classes of welding and high-temperature heating operations it is desirable to reduce the volume of the fuel gas used, in order to perform the operation more economically. The main object of this invention is to provide a gas mixer for this purpose whereby such fuel gas may be first satisfactorily and conveniently diluted with atmospheric air, after which substantially pure oxygen may be thoroughly mixed with the so-diluted fuel gas. Other objects of the invention are to provide a gas mixer of this character which is simple and compact; has a minimum of movable elements; is readily accessible for repair or replacement; and will be applicable to known blowpipe constructions without much change in the latter. The above and other objects and the novel features of the invention will become apparent from the following description and the accompanying drawing which illustrates one embodiment of the invention and in which:

30 Fig. 1 is a longitudinal mid-section of a blowpipe embodying the invention; and

Fig. 2 is a partial cross-section on the line II—II of Fig. 1.

In the embodiment of the invention illustrated in the drawing there is shown a blowpipe head H which is in general of known construction. This body or head H may be unitary, that is to say it may be made entirely of one piece as illustrated in the drawing. Conduits 10, 11 and 12 for a fuel gas such as acetylene, for heating oxygen and for cutting oxygen, respectively, connect with the rear end of the blowpipe head H in known manner, and the flow of gas through each conduit may be controlled by any preferred or usual valve arrangement (not shown).

There is also provided at the rear end of the blowpipe head H an improved mixer M to which the acetylene, the diluting air, and the heating oxygen are supplied. This construction and arrangement will be described later.

The forward end of the blowpipe head H is shown as turned at an angle and is counter-bored to provide a cavity C to receive the usual nozzle N. At the inner extremity of the cavity C there is a face 13 against which the rear face

of the nozzle N is pressed by means of a coupling nut 14 having an external thread 15 which screws into an internal thread 16 in the cavity C for securing the nozzle N to the blowpipe head H, in well known manner. The outlet of a duct 17 through the blowpipe head H registers with the inlet of a central duct 18 in the nozzle N and carries cutting oxygen from the cutting oxygen conduit 12 to the nozzle. A heating gas duct 19 in the blowpipe head H connects the outlet end 10 of the mixer M with an annular recess 20 in the inner face 13 of the cavity C; and the inner ends of ducts 21 in the nozzle N register with the annular recess 20 in every position of the nozzle when coupled to the blowpipe head. The ducts 21 carry the combustible mixture to the outer end of the nozzle N.

The mixer M comprises a bore 22 in the blowpipe head H; a communicating mixer throat 23 extending from the inner end of the bore 22 to the heating gas duct 19; and a mixer nozzle 24 disposed in the bore 22 substantially axially thereof with its inner end adjacent but spaced from the entrance to the mixer throat 23. The mixer nozzle 24 is preferably unitary or formed in a single piece as shown in Fig. 1. The nozzle 24 and the blowpipe head H form between them two annular chambers 25 and 26 in the bore 22. The nozzle 24 has a threaded section 27 intermediate its ends which screws into a corresponding threaded section in the bore thereby securing the nozzle 24 in position and separating the chambers 25 and 26. The threaded section 27 of the nozzle 24 is formed with the roots of the threads therein no deeper than the unthreaded circumferential surfaces of the nozzle adjacent thereto, and the crests of the threads extend outwardly therebeyond. Thus, when the nozzle has been screwed into place an annular chamber may be formed on either side of the threaded section between the nozzle and the inner surfaces of the bore in the blowpipe head H.

The nozzle 24 has a conical tip 28 adjacent the mixer throat 23, and a neck 29 of reduced section connects the tip to the body portion of the nozzle. A central passage 30 in the nozzle extends substantially axially through a part of the body portion, through the neck 29, through the tip 28, and has its outlet opposite the entrance of the throat 23. A connecting passage 31 extends between the central passage 30, through the unthreaded section of the nozzle body behind the threads 27, into the rear chamber 26. A duct 32 connects the chamber 26 with the heating oxygen conduit 11. Thus heating

oxygen may flow through the duct 32 into the chamber 26, thence through the connecting passage 31 to the central passage 30.

An acetylene duct 33 connects the acetylene conduit 10 with the front chamber 25.

Air for diluting the acetylene may be supplied directly from the atmosphere to the front chamber 25. For this purpose the mixer nozzle 24 may be provided with a plurality of eccentric 10 passages 34 which extend longitudinally of the nozzle body, from its extreme outer end to the circumferential recess 29' around the neck 29. The inlets of the passages 34 are thus open to the atmosphere and their outlets terminate in 15 the recess 29' which communicates directly with the chamber 25.

The outer end of the mixer nozzle 24 has a head 35 provided on its under side with a suitable annular sealing surface 36 to cooperate and provide a gas-tight fit with a corresponding sealing surface 37 at the mouth of the bore 22. The periphery of the head 35 may have a hexagon or other suitable shape to fit a wrench for removing or tightly inserting the nozzle 24 in the bore 22.

The operation of the blowpipe, embodying the improved mixer, will be apparent from the foregoing description. The heating oxygen usually supplied to the mixer at a substantially higher pressure than the acetylene, is delivered from the pipe 11 to the passage 30 and discharges therefrom at a substantial velocity across the lower end of the chamber 25 into the outlet throat 23. This produces a suction and reduces the pressure in the chamber 25 by withdrawing gas from the latter, thereby not only assisting to draw acetylene from the pipe 10 into the chamber 25 but at the same time drawing air through the passages 34 into the chamber 25 to dilute the acetylene. This mixture of acetylene and air is then entrained and carried with the oxygen stream through the throat 23 and the flaring passage 19 where the several gases are thoroughly mixed before they are discharged from the passages 21 of the nozzle N. The walls of the relatively deep annular recess 29' compel an abrupt change in the direction of the inflowing air and, together with the sharp shoulders on the nozzle 24 and the narrowness of the chamber 25, produce a turbulence in the air and acetylene which thoroughly mixes these gases.

The size of the passage 30, the width of the chamber 25, and the size and number of the passages 34 are proportioned with respect to each other to deliver a combustible mixture to the passages 21 which is appropriate for the size of the latter and the preheating or welding to be done. The blowpipe and mixer construction is particularly advantageous because both the nozzle N and the mixer nozzle 24 may be removed readily and replaced by nozzles having larger or smaller passages for operating upon heavier or lighter work.

While the invention is illustrated as embodied in a cutting blowpipe, it will be evident that it

may be incorporated in other types of blowpipes, such as those used for welding. Clearly the oxygen supply and the fuel gas supply may be transposed, and air may be mixed first with the oxygen instead of the fuel gas. Furthermore, under certain conditions the invention may be applied in connection with the use of liquids, vapors or pulverized solids. Various other changes may be made in the details of construction herein disclosed without departing from the principles of the invention.

I claim:

1. A fluid mixing nozzle comprising a substantially cylindrical body portion; a threaded section intermediate the end sections of said body portion of greater diameter than said end sections; a conical head; and a neck of reduced section connecting said head integrally with said body portion; said nozzle having a central passage therein extending substantially axially through a part of said body portion only, through said neck and through said head; said nozzle having a passage between the central passage therein and the unthreaded section of said body portion farthest from said head; and said nozzle having a passage extending longitudinally through said body portion only.

2. A fluid mixing nozzle comprising a substantially cylindrical body portion; a conical head; a neck of reduced section connecting said head integrally with said body portion; a threaded section intermediate the end sections of said body portion of greater diameter than said end sections; said nozzle having a central passage therein extending substantially axially through a part of said body portion only, through said neck and through said head; said nozzle having a passage between the central passage therein and the unthreaded section of said body portion farthest from said head, and an enlarged end integral with said body portion at the end thereof opposite the end to which said head is connected, said enlarged end having plane faces parallel to the longitudinal axis of said nozzle, said nozzle having a plurality of passages extending through said body portion only, substantially as described.

3. A blowpipe comprising a body portion having a counterbored chamber; means for conducting different gases to spaced points along said counterbored chamber; a nozzle within said counterbore provided with means at a point between said spaced points adapted to secure it therein and having reduced portions adjacent said securing means to form auxiliary chambers with said bore at said points; a conduit adapted to connect one of said auxiliary chambers with a central duct within said nozzle; means for introducing a third gas to said other auxiliary chamber comprising passages extending substantially throughout the length of said nozzle; and a baffle between the exit of said passages and the entrance of said other auxiliary chamber.
